SPECTROPHOTOMETER OR THE LIKE

John J. J. Staunton, Oak Park, Ill., assignor to Coleman Instruments, Inc., Maywood, Ill., a corporation of Delaware

Filed July 27, 1964, Ser. No. 81,039

Term of patent 14 years

(Cl. D16—2)

FIG. 1 is a front elevation of a spectrophotometer, showing my new design;

FIG. 2 is an end elevation thereof, and

FIG. 3 is a vertical sectional view thereof on the line 3—3 of FIG. 1.

The dominant features of my design reside in the portions shown on the drawing in solid lines.

This application is a continuation-in-part of my application, Serial No. D. 76,472, filed September 4, 1963, now abandoned.

I claim:

The ornamental design for a spectrophotometer or the like, substantially as shown and described.
